CLAIM

The ornamental design for a pet carrier, as shown and described.

DESCRIPTION

FIG. 1 is a top, front, right perspective view of a pet carrier, comprising a stroller, a stroller body, and a support frame, showing the carrier portion separately for complete disclosure;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom view thereof.

FIG. 8 is a top, front, right perspective view of the pet carrier, comprising a stroller, a stroller body, and a support frame, showing the stroller portion separately for complete disclosure;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and

FIG. 14 is a bottom view thereof.

FIG. 15 is a top, front, right perspective view of the pet carrier, comprising a stroller, a stroller body, and a support frame, showing the support frame portion separately for complete disclosure;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof; and

FIG. 21 is a bottom view thereof.

FIG. 22 is a top, front, right perspective view of the pet carrier, comprising a stroller, a stroller body, and a support frame, showing the carrier attached to the support frame separately for complete disclosure;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof; and

FIG. 28 is a bottom view thereof.

FIG. 29 is a top, front, right perspective view of the pet carrier, comprising a stroller, a stroller body, and a support frame thereof;

FIG. 30 is a front elevational view thereof;

FIG. 31 is a rear elevational view thereof;

FIG. 32 is a right side elevational view thereof;

FIG. 33 is a left side elevational view thereof;

FIG. 34 is a top plan view thereof; and,

FIG. 35 is a bottom view thereof.

Broken lines in the drawings depict portions of the pet carrier that form no part of the claimed design.
